FEEDING MECHANISM FOR SEWING MACHINES

Frank Parry, Bridgeport, Conn., assignor to The Singer Manufacturing Company, Elizabeth, N. J., a corporation of New Jersey

Application December 11, 1941; Serial No. 422,482

10 Claims. (Cl. 112—215)

This invention relates to improvements in work-feeding mechanisms for sewing machines and more particularly for zigzag lock-stitch sewing machines having an endwise reciprocatory and laterally vibratory needle, together with a loop-taker rotating in a plane substantially parallel to the plane of needle-vibration.

A primary object of the present invention is to provide in a zigzag lock-stitch sewing machine a feeding mechanism affording the necessary clearance to gain ready access to the loop-taker for replenishment of its thread-supply and for the employment of under bed attachments and auxiliary mechanisms.

The invention has also for its objects to provide a compactly arranged sewing machine feeding mechanism of sturdy construction and lending itself to high-speed operation of the sewing machine.

Other and more specific objects of the invention will be apparent from the following description and claims.

The invention consists in the devices, combinations and arrangements of parts hereinafter described in connection with the accompanying drawings, which illustrate a preferred embodiment of the invention and in which:

Fig. 1 is a front side elevation of the bed mechanism of a sewing machine containing the present improvement, the work-supporting plate of the bed-frame being shown in vertical section. Fig. 2 is a front end elevation of the feeding mechanism, a portion of the work-support being shown in transverse vertical section. Fig. 3 is a top plan view of the feeding mechanism, with the work-support partly broken away and with the bed-frame shown in horizontal section. Fig. 4 is a bottom plan view of the machine. Fig. 5 is a vertical transverse section taken substantially on the line 5—5 of Fig. 1 and showing the feed-advance actuating connections. Fig. 6 is a vertical transverse section taken substantially on the line 6—6 of Fig. 1 and showing the connections with the feed-lift actuating eccentric.

Referring to the drawings, the sewing machine has a frame including a work-supporting bed-plate 10 and a bracket-arm 11 rising from one end of the bed-plate 10. Suitably secured upon the bed-plate 10 is the usual throat-plate 12 provided with feed-slots, as 13, and with a needle-slot 14 which is elongated lengthwise of the bed-plate 10. Operating through the feed-slots 13 is a feed-dog 15 actuated, as hereinafter described, to advance the work crosswise of the bed-plate; the feed-dog 15 being opposed in its work-engag-

ing movements by the usual spring-depressed presser-foot 16. Operating through the throat-plate needle-slot 14 is a vertically reciprocatory and laterally vibratory needle 17 which may be actuated by any usual or suitable mechanism (not shown), whereby the plane of lateral vibration of the needle is transverse to the line of feed of the work.

Complemental to the needle 17 in the formation 10 of zigzag lock-stitches is a forwardly open loop-taker 18 of the rotary hook type having its axis of rotation extending horizontally crosswise of the bed-plate 10 and substantially parallel to the line of feed, whereby the plane of rotation of the loop-taker is substantially parallel to the plane of needle-vibration. The loop-taker 18 is preferably disposed entirely rearward of the path of needle-reciprocation and is actuated to perform two rotations for each complete endwise reciprocation of the needle 17; said loop-taker 18 being constructed to cast needle-thread loops about a thread-carrier 19 journaled in the loop-taker and suitably restrained against rotation therewith.

25 The loop-taker 18 is carried by a shaft 20 extending rearwardly from the loop-taker and horizontally journaled in suitable bearings provided in a chambered casing 21 depending from the bed-plate 10; said casing 21 being closed by an end-cover plate 22 detachably secured to the casing by screws, as 23, whereby the casing is adapted to contain a supply of lubricant. Carried by the loop-taker shaft 20, within the casing 21 and between the ends of said shaft 20, is a spiral pinion 24 engaged by a spiral driving gear 25 also disposed within the casing 21 and adapted to dip into a supply of lubricant within said casing. The driving gear 25 is suitably secured upon a horizontally disposed bed-shaft 26 extending lengthwise of the bed-plate 10 and located at the rearward side of the plane of rotation of the loop-taker. The bed-shaft 26 is rotatably journaled in a bearing-bushing 27 carried by the casing 21; said shaft 26 being also journaled between its ends in a bearing-bushing 28 secured in a lug 29 depending from the bed-plate 10. At its end opposite to the driving gear 25, the bed-shaft 26 is journaled in a ball-bearing 30 supported by a lug 31 depending from the bed-plate 10. Adjacent the lug 31, the bed-shaft 26 carries a belt-pulley 32 which is driven by a clip-belt 33 in timed relation so that the bed-shaft 26 performs one rotation for each complete needle-reciprocation.

45 The feed-dog 15 derives its work-advancing

movements from the bed-shaft 26 by means of compactly arranged actuating mechanism providing for accurately positioning the feed-dog 15 lengthwise of the throat-plate feed-slots 13 and affording ready access to the loop-taker for replenishment of its thread-supply. To this end, the feed-dog 15 is suitably secured by screws 34 upon the forward end of a horizontally disposed feed-bar 35. At its rearward end, the feed-bar 35 has a horizontally apertured boss 36 pivotally mounted upon a stud-pin 37 disposed substantially parallel to the bed-shaft 26. One end of the stud-pin 37 is carried by the upper end of an arm 38 of a feed-rocker 39 disposed at the rearward side of the plane of rotation of the loop-taker. The stud-pin has its reduced and threaded opposite end secured by a nut 40 in the upper end of a second arm 41 of the feed-rocker 39. The lower end of the feed-rocker 39 is pivotally mounted upon pintles 42, one of said pintles being adjustably secured to the casing 21 and the other pintle being adjustably secured to the bed-lug 29. The pintles 42 support the feed-rocker 39 for movement about an axis parallel to the axis of rotation of the bed-shaft 26.

The feed-bar 35 is lengthwise provided with a guide-slot 43 disposed under the feed-dog 15, in which guide-slot is slidably disposed a pivot-block 44 carried by the forward free end of a short feed-lift crank-arm 45. The crank-arm 45 has a split hub clamped by a screw 46 upon one end of a feed-lift rock-shaft 47 disposed substantially parallel to and forwardly of the bed-shaft 26. As illustrated in the drawings, the rock-shaft 47 is, nevertheless, disposed at the rearward side of the vertical plane of rotation of the loop-taker 18 between said plane and the axis 42 of the feed-rocker 39. The feed-lift rock-shaft 47 is journaled in a bearing-lug 48 depending from the bed-plate 10 in front of the bed-shaft 26; said rock-shaft 47 being also journaled in the bearing-lug 29 to extend slightly beyond said bearing-lug. Adjustably clamped by a screw 49 upon the end of the rock-shaft 47 adjacent the bearing-lug 29 is the split-hub of a downwardly extending crank-arm 50. The free end of the crank-arm 50 is connected by a pivot-bolt 51 to the forward end of a short pitman 52 having a strap 53 embracing a feed-lift eccentric 54 carried by the bed-shaft 26. Preferably, a roller-bearing 55 of the needle-roller type is interposed between the pitman-strap 53 and the eccentric 54.

In order to impart work-advancing and return movements to the feed-dog 15, the bed-shaft 26 is provided with an adjustable feed-advance eccentric 56 carried by the bed-shaft between the casing 21 and the bearing-lug 29. The eccentric 56 is structurally similar to the adjustable eccentric more fully illustrated and described in the U. S. Patent No. 2,128,031, August 23, 1938, W. Myers. In general, the eccentric 56 is carried by a guide-plate 57 shiftable diametrically of the shaft 26 in a suitable guideway provided in a driver-member 58 fast upon the shaft 26. An adjusting-member 59 disposed loosely upon the shaft 26 and suitably spring-pressed into engagement with the driver-member 58 has a cam-track (not shown) entered by a stud 60 extending from the guide-plate 57. The hub of the adjusting-member 59 has a peripheral stop-notch 61 adapted to be entered by one end of a spring-retracted detent-pin 62 endwise movable horizontally in a suitable aperture provided in the bed-lug 48. The forward end of the detent-pin

62 is adapted to be engaged by an arm 63 depending from one end of a horizontally disposed spindle 64 supported for rocking movements in the bed-lugs 48 and 29. At its opposite end, the spindle 64 carries a flattened arm 65 positioned to be engaged by a spring-retracted plunger-pin 66 extending vertically through an aperture in the bed-plate 10 so as to be accessible from the upper side of said bed-plate. When the plunger-pin 66 is depressed to cause the detent-pin 62 to enter the stop-notch 61 of the adjusting-member 59, the latter is held against rotation with the shaft 26. When the shaft 26 is now turned, the guide-plate 57 is shifted diametrically in the guideway of the driver-member 58 and the eccentric 56 is thereby adjusted as to eccentricity.

The eccentric 56 is embraced by the strap 67 of a short pitman 68; it being preferred to interpose a needle-roller bearing 69 between the eccentric 56 and the pitman-strap 67. The pitman 68 extends horizontally forwardly from the bed-shaft 26, and the forward end of said pitman is connected by a pivot-bolt 70 to the lower end of a depending crank-arm 71. The crank-arm 71 has a sleeve-hub 72 pivotally embracing the feed-lift rock-shaft 47, whereby said rock-shaft 47 constitutes the fulcrum of the crank-arm 71. Adjustably clamped by a screw 73 upon the hub 72 of the crank-arm 71 is the split hub 74 of a crank-arm 75 extending upwardly from the rock-shaft 47 and oppositely to the crank-arm 71. The crank-arms 71 and 75 are therefore coaxially fulcrumed upon the feed-lift shaft 47 and together comprise a two-armed lever having the arms thereof angularly adjustable relatively to each other. The crank-arm 75 is pivotally connected, by a pivot-bolt 76 to one end of a link 77. At its opposite end, the link 77 has a sleeve 78 pivotally embracing the stud-pin 37 of the feed-rocker, between the boss 36 of the feed-bar and the arm 41 of the feed-rocker.

It will be noted from Fig. 5 of the drawings that the axes of the rock-shaft 47 and the feed-rocker 39 are not only substantially parallel, but also that they are disposed at substantially the same level. It will be further noted that the effective lengths of the arm 75 and the feed-rocker arms 38, 41, are substantially equal, whereby a parallel-link motion effect is obtained. The described feeding mechanism is therefore very compact in its arrangement of the parts thereof rearwardly of the vertical plane of rotation of the loop-taker 18. Ready access to the loop-taker for thread-replenishment purposes is therefore afforded and the necessary clearance is provided under the bed-plate in front of the loop-taker and feed-mechanism for employment of auxiliary devices when desired. The compactly arranged feeding mechanism also lends itself to high speed operation.

By relative angular adjustment of the lever-arms 71 and 75, the feed-dog 15 may be readily repositioned endwise of the throat-plate feed-slots 13 without varying the height of the feed-dog and without changing the plane of the feed-dog teeth with respect to the plane of the work-support.

As illustrated in Figs. 5 and 6 of the drawings, the bed-shaft 26 is longitudinally provided with a bore 79 open at the end of said shaft disposed within the casing 21, which casing houses the loop-taker driving gears and also serves as a lubricant-reservoir. Loosely disposed in the bed-shaft bore 79 is a rod 80 protruding slightly from the shaft 26 within the casing 21.

In the operation of the machine, lubricant splashed by the driving gear 25 lodges upon the protruding end of the rod 80 and is conducted lengthwise of the shaft-bore 19 for delivering lubricant to the needle-roller bearings 55 and 69, in the manner more fully illustrated and described in the U. S. Patent of S. Zonis, No. 2,267,581, Dec. 23, 1941.

Having thus set forth the nature of the invention what I claim herein is:

1. Feeding mechanism for sewing machines having a frame including a work-support, a work-advancing feed-dog operating through said work-support, a feed-bar carrying said feed-dog and disposed below said work-support, a feed-rocker disposed below said work-support and pivotally connected to said feed-bar, a feed-lift rock-shaft disposed below said work-support and operatively connected to said feed-bar for imparting work-engaging and disengaging movements to said feed-dog, a rotary actuating shaft disposed below said work-support and substantially parallel to said rock-shaft, operative connections with said rotary shaft for actuating said rock-shaft, a feed-advance lever fulcrumed coaxially of said rock-shaft, a link connecting said lever to said feed-rocker independently of said feed-bar, an actuating eccentric carried by said rotary shaft, and a pitman actuated by said eccentric and operatively connected to said lever for imparting work-advancing and return movements to said feed-dog.

2. Feeding mechanism for sewing machines having a frame including a work-support, a work-advancing feed-dog operating through said work-support, a feed-bar carrying said feed-dog and disposed below said work-support, a feed-rocker pivotally connected to said feed-bar, a feed-lift rock-shaft disposed below said work-support and operatively connected to said feed-bar for imparting work-engaging and disengaging movements to said feed-dog, a rotary actuating shaft disposed below said work-support and substantially parallel to said rock-shaft, operative connections with said rotary shaft for actuating said rock-shaft, a feed-advance lever fulcrumed coaxially of said rock-shaft, said lever having a pair of arms adjustable relatively to each other, a link connecting one of the arms of said lever to said feed-rocker, an actuating eccentric carried by said rotary shaft, and a pitman actuated by said eccentric and operatively connected to the other arm of said lever.

3. Feeding mechanism for sewing machines, comprising, a work-advancing feed-dog, a feed-bar carrying said feed-dog, a feed-rocker pivotally connected to said feed-bar, a feed-lift rock-shaft disposed substantially parallel to the fulcrum-axis of said feed-rocker, a crank-arm carried by said rock-shaft and operatively connected to said feed-bar for imparting work-engaging and disengaging movements to said feed-dog, a lever fulcrumed upon said rock-shaft and having a pair of oppositely directed arms secured together for angular adjustment relatively to each other about the longitudinal axis of said rock-shaft, one of the arms of said lever being disposed substantially parallel to said feed-rocker, a link pivotally connected at its opposite ends to said feed-rocker and to the lever-arm parallel therewith, a rotary actuating shaft, a feed-advance eccentric carried by said shaft and operatively connected to the other arm of said lever for imparting work-ad-

vancing movements to said feed-dog, and a feed-lift eccentric carried by said rotary shaft and operatively connected to actuate said rock-shaft.

4. In a sewing machine having a frame including a work-support, in combination, an endwise reciprocatory and laterally vibratory needle, a loop-taker complemental to said needle in the formation of stitches and disposed below said work-support for rotation in a plane substantially parallel to the plane of needle-vibration, loop-taker actuating means including a rotary shaft disposed below said work-support at one side of the plane of needle-vibration, a feed-dog operating through said work-support for advancing work crosswise of said plane of needle-vibration, a feed-bar carrying said feed-dog, a feed-lift rock-shaft disposed below said work-support at the rotary shaft side of said plane of needle-vibration, means connected to said rotary shaft for actuating said rock-shaft, operative connections between said rock-shaft and feed-bar for imparting work-engaging and disengaging movements to said feed-dog, and operative connections between said rotary shaft and said feed-bar for imparting work-advancing and return movements to said feed-dog.

5. In a sewing machine having a frame including a work-support, in combination, an endwise reciprocatory and laterally vibratory needle, a loop-taker complemental to said needle in the formation of stitches and disposed below said work-support for rotation in a plane substantially parallel to the plane of needle-vibration, loop-taker actuating means including a rotary shaft disposed below said work-support for rotation about an axis transverse to the axis of rotation of the loop-taker, a feed-dog operating through said work-support for advancing work crosswise of said plane of needle-vibration, a feed-bar carrying said feed-dog, a feed-lift rock-shaft disposed below said work-support and substantially parallel to said rotary shaft, said rock-shaft being located between said rotary shaft and said plane of rotation of the loop-taker, means connected to said rotary shaft for actuating said rock-shaft, operative connections between said rock-shaft and said feed-bar for imparting work-engaging and disengaging movements to said feed-dog, and operative connections between said rotary shaft and said feed-bar for imparting work-advancing and return movements to said feed-dog.

6. In a sewing machine having a frame including a work-support, in combination, an endwise reciprocatory and laterally vibratory needle, a loop-taker complemental to said needle in the formation of stitches and disposed below said work-support for rotation in a plane substantially parallel to the plane of needle-vibration, loop-taker actuating means including a rotary shaft disposed below said work-support for rotation about an axis transverse to the axis of rotation of the loop-taker, a feed-dog operating through said work-support for advancing work crosswise of said plane of needle-vibration, a feed-bar carrying said feed-dog, an oscillatory feed-rocker disposed below said work-support and pivotally connected to said feed-bar, a feed-lift rock-shaft disposed below said work-support substantially parallel to the axis of oscillation of said feed-rocker and between said feed-rocker and said plane of rotation of the loop-taker, means connected to said rotary shaft for actuating said rock-shaft, operative connections between said rock-shaft and said feed-bar for imparting work-

engaging and disengaging movements to said feed-dog, and operative connections between said rotary shaft and said feed-bar for imparting work-advancing and return movements to said feed-dog.

7. In a sewing machine having a frame including a work-support, in combination, an endwise reciprocatory and laterally vibratory needle, a loop-taker complementary to said needle in the formation of stitches and disposed below said work-support for rotation in a plane substantially parallel to the plane of needle-vibration, loop-taker actuating means including a rotary shaft disposed below said work-support for rotation about an axis transverse to the axis of rotation of the loop-taker, a feed-dog operating through said work-support for advancing work crosswise of said plane of needle-vibration, a feed-bar carrying said feed-dog, an oscillatory feed-rocker disposed below said work-support and pivotally connected to said feed-bar, a feed-lift rock-shaft disposed below said work-support substantially parallel to the axis of oscillation of said feed-rocker and between said feed-rocker and said plane of rotation of the loop-taker, means connected to said rotary shaft for actuating said rock-shaft, operative connections between said rock-shaft and said feed-bar for imparting work-engaging and disengaging movements to said feed-dog, a two-armed lever fulcrumed coaxially of said rock-shaft, a feed-advance eccentric carried by said rotary shaft, a pitman having at one end a strap embracing said eccentric and having its other end pivotally connected to one arm of said lever, and a link connecting the other arm of said lever to said feed-rocker for imparting work-advancing and return movements to said feed-dog.

8. In a sewing machine having a frame including a work-support, in combination, an endwise reciprocatory and laterally vibratory needle, a loop-taker complementary to said needle in the formation of stitches and disposed below said work-support for rotation in a plane substantially parallel to the plane of needle-vibration, loop-taker rotating means including a rotary shaft disposed below said work-support at the loop-taker side of the plane of needle-vibration, a feed-dog operating through said work-support for advancing work crosswise of said plane of needle-vibration, a feed-bar carrying said feed-dog, a feed-rocker pivotally connected to said feed-bar and disposed at the loop-taker side of said plane of needle-vibration, a feed-lift rock-shaft disposed below said work-support at the rotary-shaft side of said plane of needle-vibration, means connected to said rotary shaft for actuating said rock-shaft, a crank-arm carried by said rock-shaft and operatively connected to said feed-bar for imparting work-engaging and disengaging movements to said feed-dog, and operative connections between said rotary shaft and feed-rocker at the loop-taker side of said plane of needle-vibration for imparting work-advancing and return movements to said feed-dog.

9. In a sewing machine having a frame in-

cluding a work-support, in combination, an endwise reciprocatory and laterally vibratory needle, a loop-taker complementary to said needle in the formation of lock-strokes and disposed below

5 said work-support for rotation in a plane substantially parallel to the plane of needle-vibration, loop-taker rotating means including a rotary shaft disposed below said work-support at one side of the plane of needle-vibration, a feed-dog operating through said work-support for advancing work crosswise of said plane of needle-vibration, a feed-bar carrying said feed-dog, a feed-rocker pivotally connected to said feed-bar and disposed at the rotary shaft side of said plane 10 of needle-vibration, a feed-lift rock-shaft disposed below said work-support at the rotary shaft side of said plane of needle-vibration, said rock-shaft being substantially parallel to said rotary shaft and to the fulcrum-axis of said feed-rocker, a feed-lift eccentric carried by said rotary shaft and connected to actuate said rock-shaft, operative connections between said rock-shaft and feed-bar for imparting work-engaging and disengaging movements to said feed-dog, a lever 15 fulcrumed upon said feed-lift rock-shaft, a link connecting said lever to said feed-rocker, and a feed-advance eccentric carried by said rotary shaft and connected to said lever for imparting work-advancing and return movements to said feed-dog.

10. In a sewing machine having a frame including a work-support, in combination, an endwise reciprocatory and laterally vibratory needle, a loop-taker complementary to said needle in the formation of lock-strokes and disposed below said work-support for rotation in a plane parallel to and at the rearward side of the plane of needle-vibration, a loop-taker carrying shaft extending crosswise of said work-support and disposed at the rearward side of said plane of needle-vibration, a rotary-actuating shaft disposed below said work-support to extend lengthwise thereof at the rearward side of said plane of needle-vibration, driving and driven gears connecting said shafts, a feed-dog operating through said work-support for advancing work crosswise of said plane of needle-vibration, a feed-bar carrying said feed-dog, a feed-lift rock-shaft disposed below said work-support rearward of the plane of needle-vibration and substantially parallel to said rotary shaft, connections with said rotary shaft for actuating said rock-shaft, operative connections between said rock-shaft and feed-bar for imparting work-engaging and disengaging movements to said feed-dog, a feed-advance lever fulcrumed coaxially of said rock-shaft and having a pair of oppositely directed arms secured together for angular adjustment relatively to each other about the longitudinal axis of said rock-shaft, operative connections with said rotary shaft and one arm of said lever for rocking said lever, and operative connections between the other arm of said lever and said feed-bar for imparting work-advancing and return movements to said feed-dog.

FRANK PARRY.
